MOBILE ASHTRAY

Edgar H. Barbé, Santa Monica, Calif.

Application August 6, 1936, Serial No. 94,513

1 Claim. (Cl. 248—129)

This invention relates to mobile ashtrays and particularly pertains to the type of tray shown in Patent No. 1,905,123 issued April 25, 1933.

At the present time there is a demand for an ashtray of the pedestal type which may be easily moved from place to place and which is not liable to be accidentally overturned. It is the principal object of the present invention, therefore, to provide a mobile ashtray which may be easily moved and when set in a desired position will not move therefrom due to irregularities and inclination in the surface upon which it is resting, and which furthermore will resist overturning if accidentally struck while yielding to the impact and will thereafter automatically restore itself to its upright position after the impact, the said structure being formed of a relative few parts of simple construction which may be quickly and securely assembled, and which will provide a column and base for an ashtray having the characteristics here described.

The present invention contemplates the provision of a supporting column for carrying an ashtray and elements for the accommodation of other smoking accessories, and which column is mounted upon a mobile base with relation to which it may have oscillatory movement, the column being counterbalanced so that it will be restored to its upright position, the counterbalance also acting to maintain the base in a desired position of equilibrium, said base structure being formed in two major parts receiving the counterbalance and the lower end of the column.

The invention is illustrated by way of example in the accompanying drawings, in which:

Fig. 1 is a view in front elevation and vertical section showing a form of the present invention particularly disclosing the construction of the mobile base.

Fig. 2 is a view in side elevation and vertical section showing the structure of Fig. 1 with the near side shell and its bearing removed and disclosing the counterweight arrangement.

Fig. 3 is an enlarged view in end elevation as seen on line 3—3 of Fig. 1 showing the bearing structure with the housing element removed.

Fig. 4 is a view in central vertical section drawn on an enlarged scale showing the detail construction of the fragmentary portion of the base.

Fig. 5 is a view in side elevation showing another form of the present invention in which the base is of spherical construction.

Fig. 6 is a view in front elevation showing the device of Fig. 5 with the base carrying a hemi-

spherical counterweight as indicated in dotted lines.

Referring more particularly to the drawings, 10 indicates a column mounted upon a base 11. The column may be of any desired design and construction, it being here shown as having a cylindrical receptacle 12 at the upper end of which is mounted an outwardly flaring ashtray 13 through which a tubular standard 14 extends. The upper end of the standard may be fitted with 10 a cover plate 15 flaring downwardly into the mouth of the ashtray 13 to close the opening in the bottom of the ashtray and to normally prevent communication between the cylindrical receptacle 12. This receptacle is formed with a 15 base 16 at its lower end which is vertically slideable upon the standard 14 and is held in its uppermost position by a spring 17 carried upon the standard 14 and pressing upwardly against a spider 18 secured within the receptacle and 20 through which the standard is slidably mounted. The ashtray structure is of the general design shown in Patent No. 1,833,517 entitled Ashtray receptacle and cover, and issued November 24, 1931. Any suitable fitting may be placed upon 25 the upper end of the standard 14, such as for example as a bayonet pin 19 carrying a cigar or cigarette rest 20 and a handle lighter or match holder 21. The bayonet pin 19 also acts to hold the cover plate 15 of the ashtray in position. The 30 tubular standard 14 is provided at its lower end with a fastening rod 22. This rod has an upward cylindrical portion 23 suitably fastened within the end of the standard 14 and a lower cylindrical portion 24 which extends into the bore of 35 arm 25 of a counterweight 26. The lower cylindrical portion 24 of the rod is secured within the member 25 by a set screw 27. A relative flat neck 28 occurs between and connects the portions 23 and 24 of the supporting rod 22 for a purpose 40 to be hereinafter described.

Extending transversely through the counterweight arm 25 is a bore 29 which receives suitable anti-friction bearing members such as roller bearings 30. The roller bearings receive a central axle 31 which is free to rotate within the bearings and extends outwardly from opposite sides thereof. Annular lock grooves 32 are formed circumferentially of the axle 31 and are spaced a distance from the side faces of the arm 50 25 sufficiently to accommodate washers 33. Split lock rings 34 may be seated within each of the grooves 32, one of which occurs at each side of the counterweight arm 25 thereby holding the counterweight arm against longitudinal move- 55

ment through the bore 29 while permitting the axle to rotate freely within the bearing structure. The counterweight 26 is disposed beneath the rotating axis of the axle 31 and comprises a body 35 representing a segment of a cylinder at the ends of which body, as shown in Figures 1 and 2 of the drawings, spheroidal projecting portions 36 occur.

The axle 31 projects oppositely from the lock rings 34 and there receive anti-friction bearing structures 37. These structures include cylindrical bearing cages 38 having an annular shoulder 39 adjacent their outer ends and a portion 40 protruding beyond the shoulder to extend into and to be preferably upset within a central opening 41 of a hub spider 42. The hub spiders 42, one of which is disposed at each end of the axle 31, have a set of outwardly and radially flaring arms or webs 42' terminating in an annular fastening ring 43. The spiders 42 are detachably secured upon the ends of the axle 31 by means of U-shaped lock springs 44 which extend downwardly through openings 45 in one web of the hub and outwardly through a diametrically opposite set of openings 45' in a web at the opposite side of the hub. The springs 44 thus lock the hubs 42 on to the opposite ends of the axle and fit within a lock groove 46, one of which is formed around the body of the axle adjacent to each of its ends. A conical end point 47 is formed at each end of the axle beyond the position of the groove. This will tend to spread the lock spring 44 and to permit it to move to its seat in the lock groove 46 when the structure is assembled. Interposed between the lock spring 44 and the end of the bearing structure is a suitable washer 48 which will maintain the bearing elements in a set longitudinal position.

Suitably secured to the ring 43 of the hub 42 such as by spot welding is a wheel shell 49, one of which is disposed at each end of the axle. The shells combine to provide a substantially complete enclosure for the counterweight 26 and the bearing structure. The shells may be of various forms, but are shown in Figures 1 and 2 of the drawings as having a spheroidal end portion 50 terminating in a cylindrical tire portion 51. The cylindrical portion 51 is disposed with its axis horizontal and circumscribes the counterweight 26 and the space into which it might move while swinging upon the central axis of the axle 31. The cylindrical portion may be formed with corrugations 52 which might serve as a tread for the base. It is preferable that the opposite end 55 corrugations receive tires 53 upon which the base directly rolls. These tires may have a continuous circular tread surface or may be formed with a plurality of flat tread faces 54 as indicated in Figure 2 of the drawings, and for a purpose to be hereinafter described.

The contiguous edges of the two shells 49 at inner edges of the cylindrical portions 51 are formed with inturned flanges 54' which are spaced apart as indicated at 55, the distance of 65 the space 55 being sufficient to accommodate the thickness of the neck 28 of the rod 24. Thus the rod may pass between the two shell members 49 while permitting the shell members to have independent rotation with relation to each other and with relation to the counterweight member 26. The counterweight 26 along its median portion is formed with a groove 58 which accommodates the inturned flanges 54' of the shells 49 and at the same time provides a 70 finish for the structure so that when the coun-

terweight is seen through the groove a finishing plate of circular form 59 will be observed agreeing in material and finish with the shells. Suitable countersunk screws 60 hold the member 59 in position. A portion of the space 55 occurring adjacent to the top of the shells is covered by a fitting 61 which has a hub into which the standard 14 extends. This hub terminates in an outwardly flaring flange 62 which covers the space 55 under which the ends of the finishing plate terminate and materially aids in obstructing a view of the interior of the shells and the counterweight.

In the form of the invention shown in Figures 5 and 6 of the drawings, substantially hemispherical shells 63 are provided as substitutes for the shells 49 previously described. The hemispherical shells may be formed with a tread portion 64. This tread is described on an arc concentric to the diameter of a sphere of which the two hemispherical shells 63 are formed. In this construction the bearings and the shell mountings are substantially identical with that described with reference to Figures 1, 2, 3 and 4. This counterweight, however, represents a complete segment of a sphere. This tends to maintain the base in equilibrium at all times and to insure that the column 10 will be restored to an upright position irrespective of the direction in which any force has been applied to swing it from that position. The structure, however, is mobile since the shell elements 63 may rotate upon the axle 31 as previously described.

In operation of the present invention the column 10 may be constructed and assembled as shown in Figures 1 and 2; as in Figures 5 and 6 or of any other desired design. The base is assembled by placing the axle 31 through the bore 29 in the counterweight arm 25 together with the anti-friction bearing structure 30 and then locking the axle in position by the lock rings 34. The shell elements 49 or the shell elements 63 are completely assembled with the hubs 42 carrying the bearing structures 37 and their sleeves 38. The lock wires 44 are mounted with relation to the hubs and the complete assembly is then forced on to the axle until the pointed end 47 of the axle has expanded the lock wires 44 so that these wires may register with the annular groove 46 and be locked therein. Shell structure 49 will thus be locked in a rotatable supported position on the end of the axle. By reference to Fig. 1 of the drawings it will be seen that the flanges 54' carried by the contiguous edges of members 51 set into a channel member 52 carried by the counterweight 26. The counterweight only represents a segment of a sphere while the channel member is substantially circular having a split in its circumference to accommodate the member 24. These free end 60 portions of the member 59 may be flexed so that the wheel shell can move to an embracing position with relation to the channel as shown in Fig. 1.

The shells 49 may then be fitted with rubber tires 53. These tires may be made of other material. These tires are stretched and placed in position. When the tread portion of the tires is entirely circular it will be evident that the assembled base may rotate freely over a supporting surface. This has its disadvantages, however, in that when the supporting surface is irregular or inclined there is a tendency for the base to continue to roll. If tires are used having flat faces 54 it will be recognized that unless 75

manual effort is applied the base will remain standing on the flat surfaces of the tires. This insures that the structure will remain in a set place until it is desired to move it.

5 In the form of the device shown in Figures 5 and 6 the base is spherical thus the standard 10 may be swung in the vertical plane represented by the median space 55 between the shell elements, or may be swung in any other direction and due to the balance of the counterweight the standard will be restored to an upright position.

10 It will thus be seen that the present invention is decidedly simple in construction, having relatively few parts provided by self-contained means whereby they may be quickly assembled and held together and being of a construction which will provide a mobile ashtray having material advantages over other ash trays of the column 15 type now in use.

15 While I have shown the preferred form of my invention as now known to me, it will be understood that various changes might be made in the combination, construction, and arrangement 20 of parts by those skilled in the art without departing from the spirit of the invention as claimed.

25 Having thus described my invention, what I claim and desire to secure by Letters Patent is:

30 A mobile, self-righting support including an upright standard, a counterweight to which the

lower end of said standard is secured, said counterweight having a peripheral recess, an axle journaled at its central portion through said counterweight and held against axial movement relative thereto, a rotating supporting base including complementary, substantially hemispherical shells on the axle ends and enclosing the counterweight with the edges of their adjacent ends spaced apart to form an annular channel through which the standard extends, 10 each shell being formed in a single piece with a tread portion having a flange extending inwardly into the recess of the counterweight, and each shell having therein an axial bearing structure secured to its closed end and supporting 15 one end of the axle, and an annularly shaped finishing plate within the recess of the counterweight and bridging the space between the shells at opposite sides of the standard, said finishing plate having outwardly extending flanges along 20 its sides which encompass the inwardly extending flanges of the shells, said finishing plate being secured at and along its central portion to the counterweight within the recess and having yieldable end portions projecting beyond the 25 counterweight toward opposite sides of the standard whereby assembly of the shells about the counterweight is facilitated.
